UNITED STATES PATENT OFFICE.

OTTO H. MOHR, OF KENTFIELD, CALIFORNIA.

DESIGN FOR A LIGHTING-FIXTURE.

43,886.

Specification for Design. Patented Apr. 22, 1913.

Application filed January 14, 1913. Serial No. 742,059. Term of patent 3½ years.

To all whom it may concern:

Be it known that I, OTTO H. MOHR, a citizen of the United States, residing at Kentfield, Marin county, State of California, have invented a new, original, and ornamental Design for Lighting-Fixtures, of which the following is a specification, reference being had to the accompanying drawings, forming part thereof.

Figure 1 is a vertical elevation of the lighting fixture. Fig. 2 is a vertical section

of the fixtures. Fig. 3 is a cross section on the line A—A Fig. 2. Fig. 4 is a cross section on the line B—B Fig. 2.

I claim:

The ornamental design for a lighting fixture, substantially as shown.

OTTO H. MOHR.
